[57] **CLAIM**

The ornamental design for an identification band for attachment to fire fighting hose, as shown and described.

DESCRIPTION

FIG. 1 is an exploded reduced front perspective view of an identification band for attachment to fire fighting hose showing my new design, with the broken line showing for illustrative purposes only and forming no part of the claimed design;

FIG. 2 is a front perspective view thereof;

FIG. 3 is a rear elevational view thereof; and,

FIG. 4 is a side elevational view thereof, wherein the opposite sides on a 45 degree angle is a mirror image.
